UNITED STATES PATENT OFFICE.

CAROLINE BUNKER, OF PROVIDENCE, RHODE ISLAND.

DESIGN FOR A SPOON.

SPECIFICATION forming part of Design No. 21,240, dated December 15, 1891.

Application filed November 12, 1891. Serial No. 411,741. Term of patent 3½ years.

To all whom it may concern:

Be it known that I, CAROLINE BUNKER, a citizen of the United States, residing at Providence, in the county of Providence, State of Rhode Island, have invented a new and original Design for a Spoon of which the following is a specification, reference being had to the accompanying drawing, forming part thereof.

The drawing represents my newly-designed spoon.

The leading feature of my design for a spoon is a figure a, representing the Madonna resting upon the end of the handle b of the spoon and holding the infant C in her arms. The handle b is provided with an appropriate 15 decoration, as an olive branch or leaves b', while upon the bowl d of the spoon is displayed a star e.

I claim—

The design for a spoon herein shown and described.

In testimony whereof I have signed my name to this specification in the presence of two subscribing witnesses.

CAROLINE BUNKER.
